UNITED STATES PATENT OFFICE.

FRANK E. MANAHAN, OF EAST ST. LOUIS, ILLINOIS.

BALL-BEARING JOURNAL-BOX.

SPECIFICATION forming part of Letters Patent No. 703,435, dated July 1, 1902.

Application filed September 21, 1901. Serial No. 76,105. (No model.)

To all whom it may concern:

Be it known that I, FRANK E. MANAHAN, a citizen of the United States, residing in East St. Louis, in the county of St. Clair and State 5 of Illinois, have invented certain new and useful Improvements in Ball-Bearing Journal-Boxes; of which the following is a full, clear, and exact description, reference being had to the accompanying drawings, forming part 10 of this specification.

My invention relates to a journal-box in which ball-bearings are utilized to reduce the friction consequent to the rotation of the axle-spindles in the box; and the invention consists 15 in features of novelty hereinafter fully described, and pointed out in the claims.

Figure I is a side view of my journal-box applied to the truck-frame of a railway-car. Fig. II is a vertical sectional view taken on line II II, Fig. III. Fig. III is a vertical sectional view taken on line III III, Fig. II. Fig. IV is a vertical sectional view taken on line IV IV, Fig. III. Fig. V is a perspective view of the journal-box shell and the removable slide located therein. Fig. VI is a perspective view of the slide shown in Fig. V. Fig. VII is a perspective view of the ball-holding key.

A designates a portion of a car-truck frame, 30 and B a car-wheel.

1 designates the axle-spindle, provided with a screw-thread 2 and grooved to receive a spline 3, that is held by a retaining-bolt 4, which passes through the axle-spindle and 35 spline.

5 designates the shell of the journal-box, which is of octagonal shape and is provided with an annular inwardly-projecting flange 6 at its inner end.

40 By the use of a journal-box of non-circular shape, preferably octagonal, as shown, I am enabled to mount the bearing member of the journal-box seated therein in such manner as to avoid the necessity for fasteners of any 45 description for the purpose of preventing rotation of said bearing member in the box-shell, owing to the fact of the interior of the shell and the bearing member being of corresponding non-circular shape that will not 50 permit rotation of such member. Another advantage in making the shell of non-circular shape lies in the fact that it affords flat

faces for the attachment to the truck-frame, so that the shell may be held more firmly and rigidly within such frame.

55

7 is a door hinged at 8 to the forward end of the shell 5.

9 designates an inner bearing-ring internally screw-threaded to fit the screw-thread 2 of the axle-spindle and grooved to receive 60 the spline 3, by which said ring is held in a fixed position on the spindle after it has been screwed thereonto, the spline in turn being held from displacement by the retaining-bolt 4. The bearing-ring 9 is provided with race- 65 ways 10, in which bearing-balls 11 travel.

12 designates an outer bearing-ring provided with raceways 13, located opposite the raceways 10 to receive the bearing-balls 11. The outer bearing-ring 12 is provided with a 70 shouldered annular flange 14, that projects inwardly and bears against a dust-ring 15, located between said flange and the inner end of the bearing-ring 9. The bearing-ring 12 is retained in place by a retaining-ring 16, that 75 is seated within the outer end of the shell 5 against said outer bearing-ring and is held in place by retaining-bolts 17, that pass through said ring and shell. The outer bearing-ring 12 is of sectional construction, there being 80

preferably an upper and a lower section, as seen in Figs. II and IV, the lower section of which is adjustable with relation to the upper section to compensate for the wear that may occur in the use of the journal-box, and 85 in order to accomplish such adjustment I provide set-screws 18, seated in the shell 5 and adapted to bear against the lower section of the outer bearing-ring, the set-screws being equipped with jam-nuts 19, by which they 90 are held when set. By inward movement of the set-screws 18 the lower section of the outer bearing-ring is moved upwardly to the upper section of said ring. This feature of the construction is also of merit in view of the fact that it provides for sufficient adjustment of 95

the outer bearing-ring to compensate for great wear thereof, inasmuch as when the bearing-ring has become worn to any material degree the sections may be removed and reduced by 100 cutting them away at the opposite faces of the sections, and when replaced the lower section may be adjusted with relation to the upper section to produce the requisite adjust-

ment necessary for the proper operation of the bearing-balls 11 in their raceways.

In order to provide for the introduction of the bearing-balls 11 subsequent to the assembling of the remainder of the bearing and the removal of such balls previous to the dismantling of the bearing at any time, I introduce a filler-block 20 between the ends of the retaining-ring 16, which ring is of broken form, as seen in Fig. IV, the said filler-block being held between the ends of the retaining-ring by bolts 21.

22 is a key provided with a groove 23 to receive the travel of the bearing-balls 11 and 15 provided with tongues 24, that fit in undercut grooves 12^a in the bearing-ring 12. The key 22 is set into the bearing-ring 12 longitudinally thereof and is held therein by the tongues 24, so that the groove in the key extends 20 transversely of the raceways 13 in the outer bearing-ring to receive the bearing-balls. When it is desired to insert or remove the bearing-balls, the filler-block 20 is removed and the key 22 is withdrawn from its 25 seat in the bearing-ring 12, at which time the balls may be introduced into their raceways through the space previously occupied by said key or be permitted to escape through the same space. When it is desired at any 30 time to dismantle the journal-box and remove the axle-spindles therefrom, the bearing-balls are removed from the journal-box in the manner stated, after which the bearing-rings may be withdrawn subsequent to the removal of 35 the retaining-ring 16, which is easily disconnected from the shell 5 on the withdrawal of the retaining-bolts 17. When the retaining-ring has been taken from the shell, the retaining-bolt 4 is withdrawn from the axle- 40 spindle, thus permitting the removal of the spline 3 and the extraction of the inner bearing-ring 9 by unscrewing it from the axle-spindle. The outer bearing-ring 12 may then be slipped out of the shell 5, it being understood that previous to this procedure the car-truck is suitably supported by jacking it up.

In order to permit the removal of the axle-spindles from the journal-box without removing the journal-box shell from the truck-

frame, I provide a slide 25, that is movably seated in the shell 5, so that it may be removed therefrom. The slide 25 is provided with tongues 26, that fit in the grooves 27 in the shell 5, and a flange 28, that is seated between the flanges 26 of said shell. It is also 55 provided with an extension 29, that seats between ears 30 on the shell and receives bolts 31, which pass through said ears and extension and hold the slide in position, so as to complete the shell when the journal-box is in 60 use. When it is desired to remove the axle-spindles from the journal-boxes of the car, the slides 25 are removed from the shell, and an opening is thereby produced, through which the axle-spindles pass as the axle is 65 lifted and drawn away from the journal-boxes.

I claim as my invention—

1. In a journal-box, the combination with a threaded axle-spindle, of a box-shell, an outer bearing-ring seated in said shell, an inner bearing-ring having threaded connection with said spindle, bearing-balls located between said bearing-rings, a spline by which said inner ring is held from rotation on said spindle, and means for retaining said spline, 75 substantially as described.

2. In a journal-box, the combination with a threaded axle-spindle, of a box-shell, an outer bearing-ring seated in said shell, an inner bearing-ring having threaded connection 80 with said spindle, bearing-balls located between said bearing-ring, a spline by which said inner ring is held from rotation on said spindle, and a retaining-bolt passing through said spindle and spline to hold said spline 85 from displacement.

3. In a journal-box, the combination with an axle-spindle, of a shell, an outer bearing-ring seated in said shell, an inner bearing-ring fixed to the axle-spindle, bearing-balls 90 located between said bearing-rings, a key seated in said outer bearing-ring, and a block adapted to hold said key from displacement, substantially as described.

FRANK E. MANAHAN.

In presence of—

E. S. KNIGHT,
N. V. ALEXANDER.
